UNITED STATES PATENT OFFICE.

MARTIN SEILLON AND ERNEST REUTER, OF PARIS, FRANCE.

APPLIANCE ADAPTED FOR USE AS A TAP WRENCH OR VISE.

1,410,611.

Specification of Letters Patent.

Patented Mar. 28, 1922.

Application filed May 29, 1920. Serial No. 385,343.

To all whom it may concern:

Be it known that we, MARTIN SEILLON and ERNEST REUTER, citizens of the Republic of France, residing, respectively, at Paris, France, have invented an Improved Appliance Adapted for Use as a Tap Wrench or Vise, (for which we have filed an application in France March 6, 1919,) of which the following is a specification.

10 This invention has reference to an adjustable appliance suitable for use as a tap wrench or hand vise.

The appliance comprises a pair of members adapted to be forced towards each other by screws so as to grip a tap or tool in such manner as to prevent all play. The appliance may form an ordinary tap wrench or a tap wrench with a single arm for use in difficult places as in angles or corners for example, and may also serve as a hand vise for holding a tool or a piece of work to be treated, in either of two positions at 90° in relation to each other.

25 A constructional example of the improved appliance is shown in the accompanying drawings.

Fig. 1 shows partly in longitudinal section and partly in elevation the two members forming the appliance.

30 Fig. 2 shows the members combined as a normal tap wrench;

Fig. 3 shows the members combined to form a tap wrench for use in difficult places as in corners or angles for example.

35 Fig. 4 shows the members employed as a vise and holding a piece of work to be treated; and

Fig. 5 also shows the appliance in use as a vise the piece of work held thereby being replaced by a tool held in a position perpendicular to that occupied by the piece of work shown in Fig. 4.

As will be seen from the drawings the appliance comprises two members of similar size and shape, the member 1' being formed with screw-threaded holes 2 engaged by clamping or pressure screws 3 which are engaged freely in suitable apertures in the member 1. Each said member is prolonged to form a handle 4, 4' and is formed upon its inner face with a series of grooves such as 5 and 6 suitable for gripping a piece of work in order to hold it firmly in different positions. A screw 7 adjustable in one of

the members forms a stop adapted to extend 55 any desired distance beyond the inner face of the member in which it is mounted in order to ensure the parallelism of the members 1, 1' when the tool is, as shown in Figs. 4 and 5 respectively, employed as a tap 60 wrench for use in corners and as a vise.

What we claim is:—

1. An appliance of the type described comprising a pair of members of similar size and shape and including longitudinally 65 projecting handle elements, a pair of screws engaging freely in one of said members and adapted to be threaded into the other member to clamp the members upon a desired object, said members being adapted to engage the object with their handle elements extending in a common direction or in opposite directions, the inner faces of said members being formed with grooves for gripping the object, one pair of said grooves 70 extending longitudinally inward from the ends of the said members, and another pair of said grooves extending transversely of the said members between the said screws.

2. An appliance of the type described 80 comprising a pair of members of similar size and shape and including longitudinally projecting handle elements, a pair of screws engaging freely in one of said members and adapted to be threaded into the other member to clamp the members upon a desired object, said members being adapted to engage the object with their handle elements extending in a common direction or in opposite directions, the inner faces of said members 85 being formed with grooves for gripping the object, one pair of said grooves extending longitudinally inward from the ends of the said members, and another pair of said grooves extending transversely of the said members between the said screws, and an abutment screw threaded transversely through one of said members toward the end thereof opposite to that having the longitudinal groove.

3. An appliance of the type described 100 comprising a pair of members of similar size and shape and including longitudinally projecting handle elements, a pair of screws engaging freely in one of said members and 105 adapted to be threaded into the other member to clamp the members upon a desired object, said members being adapted to en-

gage the object with their handle elements extending in a common direction or in opposite directions, the inner faces of said members being formed with grooves for gripping the object, one pair of said grooves extending longitudinally inward from the ends of the said members, and another pair of said grooves extending transversely of the said members between the said screws, 10 said members having also a second pair of

transverse grooves disposed adjacent the said end thereof, and an abutment screw threaded transversely through one of said members toward the end thereof opposite to that having the last named pair of 15 grooves.

Signed at Paris, France, this twenty-second day of March 1920.

MARTIN SEILLON.
ERNEST REUTER.
